(57) **CLAIM**

The ornamental design for an instrument panel, as shown and described.

DESCRIPTION

FIG. 1 is a front view of an instrument panel showing my new design;

FIG. 2 is a front and left side perspective view thereof;

FIG. 3 is a front and right side perspective view thereof;

FIG. 4 is a right side view thereof;

FIG. 5 is a left side view thereof;

FIG. 6 is a rear view thereof; and,

FIG. 7 is a top view thereof.

The broken lines illustrate portions of the instrument panel which form no part of the claimed design.

1 Claim, 7 Drawing Sheets
